COVERING FOR BUILDINGS

Percy E. Knudsen, Pittsburgh, and Melvin E. Toussaint, Beaver, Pa., assignors to Pittsburgh Plate Glass Company, a corporation of Pennsylvania

Application August 17, 1938, Serial No. 225,360

10 Claims. (Cl. 108—10)

The present invention relates to sheathings or coverings for buildings and it has particular relation to sheathings or coverings composed of overlapping shingle-like plates.

- 5 One object of the invention is to provide a structure of the foregoing type in which the tendency of water to creep by capillary attraction back under the lower edges of the plates is reduced or obviated.
- 10 A second object of the invention is to reduce or prevent the tendency of insect bodies and dirt to accumulate under the edges of transparent shingles of glass.

15 These and other objects of the invention will be apparent from consideration of the following specification and the appended claims.

20 In a roof or external wall of a building composed of overlapping shingle-like plates, there is a tendency of water to creep by capillary attraction back under the edges of the plates. In some cases the tendency may become so pronounced as to result in the water actually passing over the upper edge portions of the overlapping units, thus producing leaks. Detritus of various kinds is also 25 carried in and in event that the roof or wall is composed of overlapped plates of glass, the accumulation produces an unsightly appearance. This appearance may be accentuated by the bodies of insects which have crawled back under the 30 edges of the shingles and died, or which have been swept back under the shingles or plates by the water carried in by capillary attraction.

35 The present invention is based upon the discovery that if the lower edges of the plates or shingles are spaced above the upper portions of the shingles which they overlap to a sufficient degree, the tendency of water to flow by capillarity between the overlapping portion is overcome. Likewise, the tendency of dirt and foreign matter 40 to accumulate is obviated or greatly reduced.

45 For a better understanding of the invention reference may now be had to the accompanying drawing in which like numerals refer to like parts throughout and in which

45 Figure 1 is a fragmentary plan view of a typical roof to which the principles of the present invention may be applied.

50 Figure 2 is a fragmentary cross-sectional view of a portion of a roof showing the use of one convenient form of spacer unit for separating the overlapping portions of the shingle plates.

55 Figures 3, 4 and 5 are detail views illustrating several of the forms of spacing device which may be employed in practicing the invention.

55 As shown in Figure 1, a roof constructed in ac-

cordance with the invention may comprise plates 9 of any convenient dimensions, which preferably are of glass tempered by suddenly chilling plates of glass heated to a temperature of about 1100 or 1200 deg. F. by sudden application of a blast of air or by dipping them into a cooling bath. The technique involved in the tempering of plates of glass is well understood by those skilled in the art and need not be further described.

10 The units 9 preferably are approximately of diamond shape, though preferably the corners are clipped, as indicated at 10. They may comprise squares arranged in courses with one diagonal extending vertically and coinciding with the rafters 11 of the roof or frame structure. The transverse 15 corners of the units are supported upon the adjacent rafters and the lower corner of the units in each course overlap the upper edges of the units in the second course below. The horizontally opposed corners of each unit are sandwiched 20 between the corners of the units in the adjacent course.

25 The plates or shingles are shown as resting directly upon the rafters. However, they may also be supported upon transverse purlins if so desired.

30 In order to space the overlapped portions of the shingles or plates, spacers or shims 14 of metal, rubber, or the like, such as are disclosed in Figure 2, may be employed. The number and arrangement of these devices is susceptible of variation. As shown in Fig. 1, two for each of the upper edges of each plate is satisfactory. One is disposed upon each side adjacent to the upper corner of each plate. A second one is disposed slightly above each intermediate or transverse corner. It will be observed from the drawing that the shims are secured to and supported upon the upper edges of the plates in such manner that the shims upon the plates in one row engage and support the lower portions of the 40 plates in the course immediately adjacent thereto. It will also be observed that the lower edges of the superposed shingles project downwardly a substantial distance below the shims in such manner that the latter are completely overhung and 45 covered.

These spacers may be approximately of U-shape in cross sectional outline and both branches may be approximately of equal length, or as shown in the drawing one branch, e. g., the upper 50 branch 15, may be longer than the other branch. The thickness of the spacers may vary to a considerable degree, but a range of approximately $\frac{1}{8}$ to $\frac{3}{2}$ of an inch is considered to be optimum. The lesser value is sufficient to obviate capillary en- 55

trance of water, but there is still some tendency to entrap insect bodies. With a spacing of $\frac{1}{8}$ of an inch the latter difficulty is also overcome, and the general tendency of dirt to accumulate between the units is greatly reduced. If the units are disposed at any reasonable angle or pitch, e. g. 20 or 30 degrees, more or less, there is no tendency of the water to blow back under the units.

In the form of the invention illustrated in Figure 4 the spacing unit or shim 17 is formed of spring material, such as iron, steel, brass, bronze, aluminum, or the like, of relatively thin section. In order to provide for adequate spacing of the overlapping plates, the upper branch 18 of the spacing device is curved or corrugated. The number of sinuations employed does not constitute an important feature, but in the form of the invention illustrated a single reflex bend 19 of S shape is sufficient.

20 The inherent resiliency or springiness of the metal in clips of this form is sufficient to accommodate for irregularities in the thickness of the glass. Likewise the springiness permits the shingle units disposed thereupon to yield slightly to 25 impacts or to other stresses, and the possibility of breakage of the units is thus substantially reduced.

In the form of the invention disclosed in Figure 5 a spacer or shim 20 comprising a single 30 plate or bar of suitable material is provided. This shim may comprise wood, leather, rubber, artificial resins such as vinyl acetal resins, phenolic resin or the like. Preferably the material possesses a certain degree of resiliency or springiness. 35 The spacers may be secured in position by frictional contact or if preferred may be cemented or otherwise bonded to the surface of either the upper or lower units, or they may be bonded to both of them. The units may be applied to the 40 glass plates at the time the plates are laid upon the roof, or they may be secured by cements or if the units are of thermoplastic material, e. g. vinyl acetal, by application of heat and pressure. These operations may be performed in the factory in which the shingles are made. The strips 45 or bars of spacing material 20 may merely extend partially or entirely across the upper corner of shingle units, or if preferred they may extend entirely along the upper edges, in order to provide a seal against the passage of air into the 50 interior of the structure to which the units are applied.

The spacers are particularly applicable to shingles of glass and notably of tempered glass, where 55 entrance of dirt between overlapped portions produces an unsightly appearance, but under some circumstances their application to shingles or plates of annealed glass, slate, tile or other forms of roofing material may be desired. Likewise they 60 are particularly applicable to roofs composed of

diagonally disposed units, but may also be employed with units the transverse edges of which parallel the direction of the courses.

The forms of the invention herein illustrated are to be considered merely as illustrative of the 5 invention, and numerous modifications may be made therein without departing from the spirit of the invention or the scope of the appended claims.

What we claim is:

1. A sheathing construction comprising upper and lower courses of shingle-like plates of glass capable of transmitting light, said courses being contiguous, the lower portions of the plates in the upper course overlapping the upper portions 15 of the plates in the lower course, the plates in said upper course being staggered with respect to those in the lower course, to cover the upper portions of the spaces between the plates in the lower course, shims inserted between the plates in 20 the two courses, and preventing contact of the plates in one course with those in the other, said shims being supported by the upper edge portions 25 of the plates in the lower course and supporting and being completely overhung by the lower edge portions of the plates in the upper course, the shims being of a thickness sufficient to obviate the tendency of water to flow back between the plates by capillary attraction.

2. A roof structure as defined in claim 1 in 30 which the plates are of approximately diamond shape and are so laid that one diagonal of each course approximately coincides in direction with the course in which the unit is disposed.

3. A roof structure as defined in claim 1 in 35 which the plates are of glass.

4. A roof structure as defined in claim 1 in which the plates are of tempered glass.

5. A roof structure as defined in claim 1 in 40 which the plates are of glass and approximately of diamond shape.

6. A roof structure as defined in claim 1 in 45 which the shims are approximately of U shape and are clipped over an upper portion of the edge of each unit.

7. A roof structure as defined in claim 1 in 50 which the shims are approximately of U shape having the upper branch corrugated and consists of springy metal.

8. A roof as defined in claim 1 in which the 55 shims are of plates disposed between the overlapped portions of the edge of each unit and consist of a yieldable material.

9. A construction as defined in claim 1 in which the shims are about $\frac{1}{8}$ inch thick.

10. A construction as defined in claim 1 in 60 which the plates are of glass and the shims are about $\frac{1}{8}$ of an inch thick.
